(57) **CLAIM**

The ornamental design for a hollow fiber as shown and described.

DESCRIPTION

FIG. 1 is a perspective view of a hollow fiber of my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a partial enlarged sectional view of the end portion of the hollow fiber taken along the line 8-8 of FIG. 2;

FIG. 9 is a partial enlarged sectional view of the end portion of the hollow fiber taken along the line 9-9 of FIG. 2;

FIG. 10 is an enlarged sectional view taken along the line 10-10 of FIG. 6; and,

FIG. 11 is a partial enlarged sectional view of the end portion of the hollow fiber as indicated by the broken line circle of FIG. 1.

The broken lines show portions of a hollow fiber that form no part of the claimed design.

The alternate long and short dash lines are merely the boundary lines between the claimed parts and the non-claimed parts.
